US0D1015698S

(12) **United States Design Patent** (10) **Patent No.:** **US D1,015,698 S**
(45) **Date of Patent:** **** Feb. 27, 2024**

(54) **SHOE SOLE**

(71) Applicant: **Latitudes, Inc.**, Sullivan, MO (US)

(72) Inventor: **Thomas H. Dieckhaus**, Sullivan, MO (US)

(73) Assignee: **Latitudes, Inc.**, Sullivan, MO (US)

(**) Term: **15 Years**

(21) Appl. No.: **29/780,089**

(22) Filed: **Apr. 22, 2021**

(51) **LOC (14) Cl.** **02-04**

(52) **U.S. Cl.**

USPC **D2/947**

(57) **CLAIM**

The ornamental design for a shoe sole, as shown and described.

DESCRIPTION

FIG. 1 is a perspective view of a shoe sole, shown with a shoe upper environment;

FIG. 2 is a top view of the shoe sole;

FIG. 3 is a bottom view of the shoe sole;

FIG. 4 is a rear view of the shoe sole;

FIG. 5 is a front view of the shoe sole;

FIG. 6 is a side view of the shoe sole; and,

FIG. 7 is an opposite side view of the shoe sole.

The dot-dot-dash broken lines in FIG. 1 depict a shoe upper environment, which forms no part of the claimed design.

1 Claim, 2 Drawing Sheets
